UNITED STATES PATENT OFFICE.

FREDERICK W. HUNTER, OF CHICAGO, ILLINOIS.

SLEEPING-CAR.

SPECIFICATION forming part of Letters Patent No. 241,986, dated May 24, 1881.

Application filed March 7, 1881. (No model.)

To all whom it may concern:

Be it known that I, FREDERICK W. HUNTER, of the city of Chicago, in the county of Cook, and State of Illinois, have invented an Improvement in Sleeping-Cars, of which the following is a specification.

My invention has reference to railway-cars adapted to sleeping purposes; and it consists in the construction of the lower berth, which is fully set forth in the following specification and shown in the accompanying drawings. This is an improvement upon Letters Patent granted to me March 1, 1881, and numbered 238,236. The object is to so construct the berth that it can be readily disposed of under the seat-cushions and in the seat-box during the day, and when stretched from one seat-box to another during the night adapted to be put under tension.

20 In the drawings, Figure 1 is a sectional elevation of one section of the car, and shows the berth when stretched and ready for use. Fig. 2 is a plan of same.

A are the seat-backs, B the seat-boxes, and C the cushions. Secured to one seat-back, above the box, are a series of hooks, D, and secured in the other seat box or back is a tension-roller, E, which is journaled at F, and is provided with a ratchet-wheel, G, into the 25 teeth of which a pawl, H, works, the end of the journal F being made square to allow of its being rotated by a crank. This roller E is provided with a series of hooks, I, or their equivalents, arranged in a longitudinal line.

30 The mattress J is preferably made of woven wire; but, if desired, may be made of canvas, or may consist of any other form of wire mattress. To one or both ends of this mattress are secured springs K. At one end the springs 35 may be connected to the hooks D direct, or, if desired, be secured to a metal or other rod, M, which, in turn, is secured loosely to the hooks and capable of detachment. The springs on the other end may be connected either to a 40 sheet of canvas or other flexible material, L, or to a series of flexible bands, which are provided with rings to catch on hooks I on tension-roller E.

If desired, the end of the canvas or flexible 45 bands may be secured to an iron rod, N, provided with means to secure it to the tension-

roller; also, the springs K may be dispensed with and the mattress made of springs.

In using this bed the bar M is hooked to the seat-back on hooks D, and after being spread out the bar N is hooked to the tension-roller 55 E, which is then rotated, stretching the springs K and putting the same under tension.

To store away the bed during the day the pawl is raised and the tension-roller is rotated 60 in the opposite direction, the bar N unhooked, the mattress folded or rolled up and deposited in the seat-box opposite, as indicated in dotted lines, Fig. 1, and the cushions are put in place.

65 The bedding and pillows may also be stored in the seat-boxes during day-time.

I am aware of the patent to Paige; but it differs greatly from my invention, and I claim nothing set forth in his patent.

70 Having now described my invention, what I claim as new, and desire to secure by Letters Patent, is—

1. A mattress for sleeping-cars, consisting of a spring-wire mattress or its equivalent detachably hooked or otherwise secured to one seat-back, and secured to a tension device in the opposite seat-box, when in use, in combination with two seat-boxes and their backs, substantially as and for the purpose specified. 75

2. In a sleeping-car, a mattress provided with springs, adapted to be folded up and deposited in a seat-box during the day and hooked to one seat-back at one end, and to a tension-roller in the opposite seat-box at the other during the night, substantially as shown and described. 80

3. In a railway-car, a spring-bed composed of springs K, canvas or wire mattress J, bar M, cloth L, and bar N, substantially as and 90 for the purpose specified.

4. In a railway-car, a tension-roller, E, attached to the seat-back A and journaled at F, provided with ratchet-wheel G, pawl H, and hooks I, or their equivalent, in combination 95 with a mattress provided with springs secured at the end to the opposite seat-back, substantially as and for the purpose specified.

5. In a railway-car, a spring-bed composed of the following parts: hooks D, secured to one seat-back, to which are attached springs K, mattress J, and cloth L, in combination 100

with tension-roller E, provided with hooks I, substantially as and for the purpose specified.

6. In a railway-car, a spring-bed which is hooked or otherwise attached to the seat-back, and in day-time rolled or folded up and loosely deposited in seat-box B, and at night drawn out and attached to a tension-roller secured to seat-back opposite, in combination with the

seat-boxes, substantially as and for the purpose specified.

In testimony of which invention I hereunto set my hand.

FREDERICK W. HUNTER.
